UNITED STATES PATENT OFFICE.

LUCIEN ARISTIDE JEAN JOSEPH REY AND FRANÇOIS VICTOR ANDRÉ JOSEPH REY,
OF ROQUEFORT-SUR-SOULZON, FRANCE.

CHEESE-SLICING MACHINE.

Application filed March 8, 1923. Serial No. 623,677.

To all whom it may concern:

Be it known that we, LUCIEN ARISTIDE JEAN JOSEPH REY, a citizen of the Republic of France, and a resident of Roquefort-sur-Soulzon, France, and FRANÇOIS VICTOR ANDRÉ JOSEPH REY, a citizen of the Republic of France, and a resident of Roquefort-sur-Soulzon, France, have invented new and useful Improvements in Cheese-Slicing Machines, which improvements are fully set forth in the following specification.

Our invention relates to certain improvements in cheese slicing machines, and more especially in machines of the type which is the subject matter of the French Rey Patent No. 516,023 issued on the 26th day of May 1920.

In order to make our improvements more clearly understood we propose to give a full description of the complete machine embodying the improvements, and we have appended hereto drawings illustrating as an example, a method of practical construction of the improved machine.

In the said drawings:

Figure 1 is a plan view of our machine.

Figure 2 is an elevation of the same with part broken off to disclose the inside mechanism.

Figure 3 is a second elevation thereof, showing certain stop devices which are not represented by Figure 2.

Figure 4 is a view of the mounting of the wire that serves to slice the cheese vertically.

Figures 5 and 6 are respectively an elevation and a plan of the wire that serves to slice the cheese horizontally.

Figures 7 and 8 are plan and sectional views of the socket carrying the said mounting.

Figure 9 is a plan view of a shovel designed to receive the cut slice of cheese.

Figure 10 is an elevation of the movable shutter limiting the shifting of the cheese when a slice has to be cut.

Figure 11 shows in plan a second movable shovel serving to handle the cheese.

Figures 12, 13 and 14 illustrate various steps in the handling of the cheese by means of the said second movable shovel.

Figure 15 is a perspective view of a com-

plete machine showing the modified form of guide shutter.

In all the drawings and figures, the same references denote the same parts.

As shown, the machine comprises a plate *a* to which is secured by means of screws *b*, or any other suitable device, a stud *c* supporting a slide. A slot *d* corresponds to the slide and runs along the whole diameter of the plate. Into this slot *d* and in the slide can be introduced a rod of suitable section *e* which carries at one of its ends a handle *e'* on which support *f* is mounted. Between support *f* and rod *e* is stretched a steel wire *g*, hooked at *g'* or at *g''* to notches on rod *e*.

On plate *a*, is provided a groove *h*, which, as shown by Figure 1, extends around about half a circumference, from *i* to *j*. Said groove *h*, which is of substantial width, receives a conveyor *h'* mounted on a rod *k* linked to a lever *l*, which, by means of a cap *l'* is adapted to pivot round a ring or collar fitted on stud *c*, such collar being rotatable round said stud.

For using the machine, rod *e* is first introduced into slot *d* and, after placing the cheese on plate *a*, rod *e* is pulled so as to cut the cheese into equal parts by means of steel wire *g*. The part of the cheese on the right hand side (Figure 1) is then removed. The receiving shovel shown by Figures 9 and 10 is next positioned on plate *a*, so that part *m m'* coincides with the diameter of the plate *a* above slot *d*.

The shovel is fitted with a handle *o* for carrying about. On said shovel is provided a slot *o'* in which is fitted a tenon *p* having a flared part *p'* which moves under the shovel opposite slot *o'*. Said tenon *p* receives the front edge of a partition adapted to pivot at *m*. As will be apparent, shifting tenon *p* along slot *o'* varies angle *z*. The value of the angle *z* determines the size of portion to be sliced from the cheese. Partition *q* is therefore positioned in such a manner that angle *z*, so formed, will correspond to the angle formed by the sides of the portions sliced from the cheese.

Partition *q* is therefore positioned in such a manner that angle *z*, so formed, will correspond to the angle formed by the sides of the portions sliced from the cheese. The partition having been set accordingly, action on handle *l'* lifts lever *l* and thereby sector *h'*, thus releasing the cheese from the top of plate *a*.

Sector h' is then revolved until the fore-edge of the Roquefort cheese's half comes against partition q . Sector h' is then free to return to the groove provided in the plate 5 to receive it; it is brought back by shifting it within the groove, so as not to drag the cheese back with this return movement. Action on handle e' of rod e causes the piece of cheese to the right of slot d to be cut, and 10 the piece so cut off is removable from plate a by means of the movable shovel operated by means of handle o .

The operation can thus be repeated until the piece of cheese has been entirely sliced, 15 care being taken to bring after each cut, rod e to the proper position for effecting another cut.

When, after the cheese has been severed into two equal parts, the right half of the 20 cheese is to be removed in order to permit slicing of the left half, the removal may be made by hand. But when, later on, the removed half is desired to be sliced, it has to be put back on the left hand side part of 25 plate a .

These two operations, that is to say, removal of the right half of the cheese and replacing the same on the left part of the plate, can also be effected by means of the 30 shovel shown by Figures 11, 12, 13 and 14, which permits the cheese to be manœuvred untouched by hand or fingers.

Said movable cheese-manœuvring shovel is made up of two half-disks A and B 35 jointed at their center by an articulation C , disk B being adapted to pivot so as to come over disk A as shown by Figure 12. Half-disk A is provided with a handle D . Half-disk B is provided with two knobs or cleats 40 E and F permitting a grip to be obtained for revolving it.

Manœuvring of the cheese by means of the said shovel is effected as follows:

The cheese form is placed entire, previous 45 to any cutting, on the shovel folded as shown by Figure 12, and the whole is carried to the plate of the machine, disks A and B being superimposed on the right hand side part of the said machine plate.

At this time, one half of the cheese rests 50 on the left hand side part of the machine and the other half on the folded shovel.

After severing the cheese in two, as hereinbefore described, the shovel has but to be 55 lifted off to remove from the plate the right hand side half of the cheese, without the latter having to be fingered (Figure 13).

The part of the cheese that remains on the machine is then sliced off as described at the 60 beginning of this specification.

In order to slice off in the same manner the removed part of the cheese, it is brought back to the machine by means of the shovel.

The shovel and the cheese being arranged 65 as illustrated by Figure 13, half-disk B

carrying the half of the cheese remaining to be sliced is revolved, so as to position the whole as shown by Figure 14.

One has then but to carry the whole on to the plate of the machine (half-disk A on 70 the right hand side of the plate) and to hold the cheese by means of the mobile shutter and to withdraw towards the right the shovel by sliding it along the plate of the machine, in order to have the half-cheese on 75 the left-hand part of the machine plate, ready for slicing.

The two knobs or cleats E and F , integral with half disk B , permit the latter to be readily rotated in the course of the above 80 described operations.

In order to avoid during slicing any shifting of the piece of cheese, I mount on the periphery of plate a a guide t (Figure 3) 85 against which the cheese bears, and this guide thus prevents any shifting of the cheese during slicing.

Said guide-shutter t must be of suitable height to hold the cheese while the latter is being cut vertically.

But when horizontal cutting is desired to be effectuated as hereinafter explained, the said guide-shutter might prevent the passage of the horizontal cutter, while the latter is being rotated in a horizontal plane parallel to plate a .

For horizontal cutting, guide-shutter t has therefore to be replaced by a guide shutter of suitable height, lower than the height of the guide-shutter used for vertical cutting.

We may, however, use a special guide-shutter (Fig. 15) permanently secured to the plate of the machine, such constructed in two parts: one part t^1 of suitable height for horizontal cutting, and permanently secured to the plate of the machine, and a second part t^2 , adapted to be secured to the first by means of a screw pin t^3 , so that the two parts together form a guide shutter of suitable height for vertical cutting.

The said two parts t^1 , t^2 constituting the guide-shutter may be readily assembled together, in any suitable manner, the part t^1 being provided with a groove engaging a rib formed on the part t^2 , or equivalent means being provided.

In order to slice the cheese horizontally, we use a cutter constituted by a supporting crutch, from which a steel wire is stretched, such cutter pivoting in a socket secured to the plate of the machine, so that the cutter-wire moves in a plane parallel to plate a of the machine and thus slices the cheese on that plane.

The height of this plane above the plate of the machine may be varied as desired by raising or lowering the supporting crutch by means of a bolt, screwing into the socket secured to the plate and constituting the bottom thereof.

The cutter, as shown by Figures 5 and 6, is composed of a rod 1, one of the ends of which is fitted with an operating handle 2 and the other end with overhanging part 3, cylindrically shaped, engages in a socket carried by the plate of the machine.

5 The cutter-wire 4 is stretched between the crutch and the handle by means of a hook 5 on the one hand and of a stretching device 6 on the other hand.

10 Wire 4 may be in the plane formed by parts 1 and 3 or, preferably, be at an angle to this plane as shown by Figure 6. It must however be parallel to part 1, so as to slice 15 the cheese horizontally.

15 The support of the cutter is constituted by a cylindrical socket 7 provided with a tongue 8 perforated with an eyelet 9. Said tongue and eyelet serve to secure by means 20 of a bolt the socket 7 to the plate of the apparatus at a point of the latter's periphery. Into the threaded lower end 10 of the socket screws a bolt 11 provided with a milled head.

25 Socket 7 being secured to the plate of the machine, the end 3 of the cutter has but to be introduced into it to slice the cheese horizontally, said end 3 bearing against end 12 of the bolt. The cutter can then freely rotate in its socket, wire 4 slicing the cheese 30 in a horizontal plane parallel to the plate of the machine.

35 By screwing more or less bolt 11, the height of the cutter wire 4 above the plate can be adjusted. Said height would be on an average about $1\frac{5}{16}$ inch for the size of the herein described parts, obviously, however, it can be varied according to the size of the cheese to be sliced.

40 It must be clearly understood that the above description is meant merely as an example of the improved machine and that

many constructional modifications may be made thereto without departing from the scope of the invention.

45 The same remark applies to the several parts serving to handle and to slice the cheese.

50 Moreover, the machine considered here as chiefly intended for slicing Roquefort cheese, can be used for slicing any cheese; the size of the plate as well as the various parts having, of course, to be adapted to the size and shape of the cheese to be sliced.

55 Machines can also be made within the scope of this invention, to slice the cheese horizontally only by means of the afore described cutter pivoting in a socket, and such machines would not include any device for vertical slicing.

60 What we claim is:

65 A machine for slicing cheese vertically and horizontally comprising: a horizontal plate with a diametrical slot therein, a cutting member mounted in the slot, a cheese conveying member mounted in the plate, a steel wire carried on the cutting member to slice the cheese vertically and moving in the diametrical slot of the plate; a movable shovel with an adjustable shutter to receive and carry away the cut cheese slices; a socket secured at the periphery of the plate, an adjusting screw or bolt in the socket, 70 a supporting member pivoted in the socket, a wire supported on the said member for horizontal cutting; and a guide-shutter, made of two parts serving to hold the cheese during vertical and horizontal slicing.

75 In testimony whereof we have signed this specification.

LUCIEN ARISTIDE JEAN JOSEPH REY.

FRANÇOIS VICTOR ANDRÉ JOSEPH REY.
